MINE LOCOMOTIVE

Robert L. Barry, Downers Grove, Ill., assignor to
 Goodman Manufacturing Company, Chicago,
 Ill., a corporation of Illinois

Application July 8, 1940, Serial No. 344,406

2 Claims. (Cl. 105—59)

This invention relates to improvements in mine locomotives, and more particularly relates to an improved means for increasing the continuous rating of a given size explosion-proof motor particularly adapted for use in propelling a mine locomotive underground.

Mine locomotives and other machines such as electric cutting or loading machines adapted for operation underground, due to space limitations in the mine, must be of confined dimensions in order to be readily maneuverable about the mine. This limits the size of the motors which can be used for propelling them. The continuous ratings of mine locomotives have heretofore been increased without increasing the size of the motor, by the circulation of air through the motor by means of a blower, but a blower cannot be used where the locomotive is operating in an explosive atmosphere for the reason that the motor casing must be totally enclosed and it would be dangerous to open the motor and draw in air from an explosive atmosphere and blow it onto the commutator and motor windings. It also is dangerous to blow a large volume of air directly over the motor casing, to cool it, for the reason that the discharge of the air into the atmosphere is apt to stir up the explosive dust and cause an explosion.

The principal objects of my invention are to provide a means for increasing the continuous rating of a given size of enclosed explosion-proof motor by the expansion of a refrigerant around the motor casing.

A more specific object of my invention is to increase the continuous rating of an enclosed motor adapted to serve as the motive power for a mine locomotive or other machine underground and of the type safe for use in an explosive atmosphere, by absorbing the heat generated by the motor losses by a refrigerant and transferring this heat to the relatively cool frame of the machine.

Other objects of my invention will appear from time to time as the following specification proceeds and with reference to the accompanying drawing wherein:

Figure 1 is a diagrammatic view in side elevation of a mine locomotive, with certain parts broken away and in section in order to illustrate certain details of my invention;

Figure 2 is a transverse sectional view of the locomotive taken substantially along line 2—2 of Figure 1, with certain parts of the motor casing broken away and shown in transverse section;

Figure 3 is an enlarged detail view of the motor casing, showing certain details of the expansion duct around the motor casing;

Figure 4 is a sectional view taken substantially along line 4—4 of Figure 2; and

Figure 5 is a view in side elevation of a mine locomotive showing a modified form of my invention.

In the embodiment of my invention illustrated in the drawing, a mine locomotive generally indicated by reference character 10 is provided. Said locomotive includes a frame, herein shown as being made up of side plates 11, 11 connected together by bottom plates 12, 12 and end bumpers 13, 13. The construction of said locomotive frame is of a type well known to those skilled in the art, so will not herein be shown or described in detail.

An electric motor 15 is provided to drive the track wheels of the locomotive. Any suitable electric traction motor may be provided and any suitable drive connection may be provided from the motor to the track wheels; or a motor may be provided for each set of track wheels, if desired; but for the purposes of simplicity I prefer to show a single electric motor provided with an armature pinion 16 which meshes with a pair of spaced apart spur gears 17, 17 meshing with gears 18, 18 having driving connection with the axles of the locomotive.

Referring now in particular to the novel features of my invention, the motor casing is herein shown as being surrounded by a member 20 having outer walls spaced from said casing and 35 having inwardly extending flanges 21, 21 secured to said casing to form a duct or expansion chamber through which a refrigerant may be circulated. Said frame member may be secured to said motor casing in a suitable manner such as welding, to provide a gas-tight connection between said casing and frame member. A pipe 22 leads from the lower end of said duct to a compressor 23. Said compressor is driven from a suitable electric motor 24 and may be of any commercial form well known to those skilled in the art, so will not herein be shown or described in detail. A pipe 25 leads from said compressor to condensing coils 26. Said condensing coils are mounted upon one of the side plates 11 of the locomotive frame, to transfer the heat transferred to said coils by the refrigerating medium to the cooler locomotive side plate and to restore the refrigerant to its proper state for expansion again over the motor shell. From said condenser 50 the refrigerating medium passes through a re-

ceiver 27, an expansion valve 28, to the duct extending around the motor casing, which forms an evaporator for the refrigerating medium.

It may be seen from the foregoing that the expanded gases in the duct 26 are drawn from said duct by the compressor 29 and compressed and passed through the condensing coils 26, 25 on one of the locomotive side plates, to transfer the heat from said gases to said side plate as said gases condense, and that the refrigerating medium expanding over the motor casing lowers the temperature thereof. The temperature of the motor may thus be controlled by the refrigerating medium and maintained at a temperature sufficiently low to increase its horse power without injuring the insulation of the locomotive. It may also be seen that the heat generated by the losses of the motor is absorbed by the refrigerant and transferred to the large side frames of the locomotive, thus providing a means for lowering the temperature of the motor without directing an air stream on the windings of the motor proper or without directing a large volume of air on the motor casing and rendering the mine atmosphere dangerous due to the stirring up of the dust therein, as discharged over the motor casing.

In the embodiment of my invention shown in Figure 5, air taken directly from the atmosphere is used as a refrigerant. In this form of my invention, a duct 29 is provided around the motor casing. A pipe 30 leads to said duct at one side of the motor casing, and an opening to the air, indicated by reference character 31, is provided from said duct at the side of the motor casing opposite from said pipe, to permit the circulation and expansion of air around said motor casing. If desired, said opening may be dispensed with and the air may be recirculated through the system. A compressor 32 is provided to compress the air, and cooling or condensing coils 33 are mounted along one side plate 11 of the locomotive frame. From said condensing coils the air passes through a receiver 34, an expansion valve 35, to the duct 29, and is expanded and circulated

around the motor casing and out of the opening 31.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In an electric motor and in combination with a mine locomotive having a frame, a casing for said motor and means for increasing the continuous rating of said motor without increasing the size thereof comprising means for absorbing the heat generated by the losses of said motor by a refrigerant and transferring it to the frame of said locomotive, including a duct extending along the outside of said motor casing and serving as an evaporator or expansion chamber, a compressor for circulating a refrigerant through said duct and condenser coils mounted on and having engagement with said frame to transfer the heat in said refrigerant to said frame.

2. In an electric motor and in combination with a mine locomotive having a frame, a casing for said motor and means for increasing the continuous rating of said motor without increasing the size thereof comprising means for absorbing the heat generated by the losses of said motor by a refrigerant and transferring it to the frame of said locomotive, including a duct extending around the outside of said motor casing and forming an evaporating chamber extending therearound, a compressor for circulating a refrigerant through said duct, and condenser coils interposed between said compressor and duct and mounted on and having continuous engagement with a side frame member of said locomotive, to transfer the heat in said refrigerant to said frame.

ROBERT L. BARRY.
